CLAIM

The ornamental design for an aircraft cabin structure, as shown and described.

DESCRIPTION

FIG. 1 is a top, right perspective view showing an aircraft cabin structure according to an embodiment of our design shown with cabin elements in broken lines;

FIG. 2 is a left side elevation view of the aircraft cabin structure of FIG. 1 shown with the cabin elements removed;

FIG. 3 is a top plan view thereof;

FIG. 4 is a section view thereof, taken along line 4—4 in FIG. 3;

FIG. 5 is a section view thereof, taken along line 5—5 in FIG. 3;

FIG. 6 is a section view thereof, taken along line 6—6 in FIG. 3;

FIG. 7 is a section view thereof, taken along line 7—7 in FIG. 3;

FIG. 8 is a top, right perspective view showing an aircraft cabin structure according to another embodiment of our design shown with cabin elements in broken lines;

FIG. 9 is a left side elevation view of the aircraft cabin structure of FIG. 8 shown with the cabin elements removed;

FIG. 10 is a top plan view thereof;

FIG. 11 is a section view thereof, taken along line 11—11 in FIG. 10;

FIG. 12 is a section view thereof, taken along line 12—12 in FIG. 10;

FIG. 13 is a section view thereof, taken along line 13—13 in FIG. 10; and,

FIG. 14 is a section view thereof, taken along line 14—14 in FIG. 10.

Throughout the Figures, broken lines showing environment or structure are for illustrative purposes only and form no part of the claimed design. Unshaded surfaces do not form part of the claimed design. Dash-dot broken lines represent the boundary between claimed and unclaimed areas and form no part of the claimed design.
